UNITED STATES PATENT OFFICE

GEORGE M. D. MANAHAN, OF NEW YORK, N. Y.

MOTHPROOF BAG.

No. 806,549.

Specification of Letters Patent.

Patented Dec. 5, 1905.

Application filed July 24, 1905. Serial No. 271,036.

To all whom it may concern:

Be it known that I, GEORGE M. D. MANAHAN, a citizen of the United States, and a resident of New York city, borough of Brooklyn, in the county of Kings and State of New York, have invented a new and Improved Moth-Proof Bag, of which the following is a full, clear, and exact description.

The invention relates to moth-proof bags such as shown and described in the Letters Patent of the United States No. 785,507, granted to me on March 21, 1905.

The object of the present invention is to provide a new and improved moth-proof bag which is perfectly moth-proof and air-tight and is provided with garment-supporting means arranged within the bag for supporting garments therein, said means extending to the outside of the bag to permit suspending the latter and its contents from a hook or other support, thus relieving the material of the bag of all undue strain, and hence insuring long life to the moth-proof bag.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvements. Fig. 2 is an enlarged transverse section of the same on the line 2-2 of Fig. 1. Fig. 3 is a perspective view of the clamping-bars. Fig. 4 is an enlarged cross-section of the improvements on the line 4-4 of Fig. 1. Fig. 5 is a perspective view of one of the supplementary closing devices. Fig. 6 is a perspective view of the back plate for the garment-support; and Fig. 7 is a face view of the blank for forming the bag-body, the garment-support being also shown in position.

The bag-body A, of paper or other suitable fabric material, is adapted to be closed at its mouth by a pair of clamping-bars B B', connected with each other at their ends by springs, preferably in the form of elastic bands B², serving to draw the clamping-bars toward each other. The clamping-bars B B' are slightly longer than the width of the bag-body A to permit of passing the mouth of the bag-body between the clamping-bars.

In practice I prefer to wrap the mouth of the

bag-body around the clamping-bar B, so that the terminal of the mouth lies on the inner face of the bar B and a portion of the mouth extends down over the said terminal and is pressed against the same by the other clamping-bar B', thus perfectly closing the mouth of the bag-body to prevent the entrance of insects, dust, &c., into the bag-body and the garments supported therein. For bag-bodies of considerable width I prefer the use of supplementary closing devices C at points a distance from the ends of the bars B B', each closing device C being preferably formed of an elastic band C', having stiff end pieces C², of cardboard or other material. The end pieces C² are pushed between the sides of the bag-body and the clamping-bars B B', so that the band C' extends over the bars in a transverse direction to assist the spring-bands B² in keeping the bars B and B' in a closed position.

The garments to be supported within the bag-body A are hung on hooks D D', of which the hooks D are hung on a flexible support, preferably in the form of a string or chain E, while the hook D' is hung on a bar D², having open eyes D³ at its ends for engaging the string E, as plainly illustrated in Figs. 6 and 7. The string E extends through spaced apertures or eyelets F', formed in sets in the back plate F, and through apertures in washers G, held between the back plate F and the reinforced portion A' for one of the sides of the bag-body A, the said reinforced portion A' having a set of registering apertures A² for the passage of the ends of the string E to the outside of the bag-body. By the arrangement described it will be seen that the portion of the string E in front of the back plate F is in the form of a loop E' for receiving and supporting the hooks D D and bar D², while the terminals of the string E extend to the outside of the bag-body and form suspending means for supporting the moth-proof bag from a hook or other support in a closet or the like in which the moth-proof bag and its contents are stored. The set of apertures A² may be formed in the side of the bag-body either nearer to or farther from the mouth of the bag-body A, as indicated in dotted lines in Fig. 1, to permit of bringing the loop E' of the garment-supporting string E and the back plate F higher up or lower down within the bag-body, according to the shape of the garments to be stored in the bag-body A. In

a like manner the string E may be engaged with any one of the sets of apertures F' to bring the back plate F higher up or lower down in the bag-body A.

5 By reference to Figs. 2 and 7 it will be seen that the side of the bag-body A through which passes the string E to the outside has reinforcing portions A' both at the inner and outer faces. The ends of the string E at the 10 outside of the bag-body are laced in apertures B³ in the bar B', and then the terminals of the string E are connected with a hanger H, in the form of a ring or the like, adapted to engage a hook in the closet in which the 15 bag and its contents are stored. If desired, the string E after being laced with the bar B' can be tied into a knot or a bow, and hangers H' H², such as shown in Fig. 1, may be engaged with the tied end of the string E to 20 suspend the moth-proof bag from a hook in the closet.

On the inner faces of the sides of the bag-body A are secured pockets I and I' for containing envelops filled with suitable disinfectant material; but as these pockets and their contents are similar to the ones shown and described in the patent above referred to it is not deemed necessary to describe the same in detail.

25 30 In using the moth-proof bag the garments are placed in the bag-body A at a time the clamping-bars B and B' are detached from the bag-body, and consequently the mouth of the latter can be readily opened for placing the garments into the bag-body. By having the hooks D and D' within the bag-body it is evident that the hangers of the garments can be readily engaged with the said hooks, so as to suspend the garments 35 40 within the bag-body. After the garments are suspended in the manner described the user pulls on the outer ends of the string E, so as to draw the inner or loop portion of the string E and likewise the back plate F in firm 45 50 position against the inner face of the corresponding side of the bag-body. When this has been done, the mouth of the bag-body A is wrapped around the clamping-bar B in the manner previously described and shown in 55 60 Figs. 1 and 2, so that the two clamping-bars securely close the mouth of the bag. The ends of the string E are laced with the outermost or unwrapped clamping-bar B', and the terminals of the said string are engaged by 65 70 hangers for supporting the bag and its contents from a hook in the closet. After the bag-body is closed by the clamping-bars B and B' and the string E is properly laced with the clamping-bar B' the user may apply 75 80 the additional or supplementary closing devices C between the ends of the clamping-bars to insure a perfect closing or sealing of the bag-body. The bag-body A is of such size that it readily contains a garment without 85 90 requiring folding thereof to keep the garment

in proper shape while contained in the moth-proof bag. The bags when empty can be readily folded up lengthwise, so as to occupy comparatively little space for shipping and storing purposes.

70 75 80 85 From the foregoing it will be seen that garments—such as coats, vests, trousers, skirts, shirt-waists, and the like—can be readily stored in the moth-proof bag and without danger of moths or other insects or dust passing into the bag and to the garments contained therein. By rendering the bag airtight it is evident that the garments contained therein are kept perfectly dry, and the disinfectant used within the bag-body is very effective without either spotting or soiling the garments contained in the bag.

Having thus described my invention, I claim as new and desire to secure by Letters Patent—

85 90 95 1. A moth-proof bag comprising a bag-body, a clamping device for closing the mouth of the bag-body, and a garment-support within the said body and extending through the side of the bag to the outside thereof to engage the said clamping device to relieve the bag-body of undue strain.

100 105 110 115 2. A moth-proof bag comprising a bag-body, a pair of clamping-bars yieldingly connected with each other and adapted to engage and close the mouth of the said bag-body, one of the bars being wrapped up in the said mouth of the bag-body and a part of the bag-body extending between the clamping-bars, and a flexible garment-support extending through one side of the bag-body to the inside thereof, the outer portion of the said flexible garment-support being connected with the outer clamping-bar.

120 125 130 135 3. A moth-proof bag comprising a bag-body having a portion of one of its sides reinforced, the reinforced portion being apertured, and a garment-support comprising an apertured back plate within the bag-body and a flexible support extending through the apertures of the said reinforced portion and the said back plate, the outer ends of the flexible support forming suspension means for the moth-proof bag.

4. A moth-proof bag comprising a bag-body having a portion of one of its sides reinforced, the reinforced portion being apertured, a garment-support comprising an apertured back plate within the bag-body and a flexible support extending through the apertures of the said reinforced portion and the said back plate, and a closing device for closing the mouth of the said bag-body and engaged by the outer ends of the said flexible support.

140 145 150 155 5. A moth-proof bag comprising a bag-body having a portion of one of its sides reinforced, the reinforced portion being apertured, a garment-support comprising an apertured back plate within the bag-body and

a flexible support extending through the apertures of the said reinforced portion and the said back plate, a closing device for closing the mouth of the said bag-body and engaged by the outer ends of the said flexible support, and a hanger connected with the said outer ends of the flexible support for suspending the moth-proof bag from a suitable support.

5 6. A moth-proof bag comprising a bag-body having a portion of one of its sides reinforced, the reinforced portion being apertured, a garment-support comprising an apertured back plate within the bag-body and a flexible support extending through the apertures of the said reinforced portion and the said back plate, and a pair of clamping-bars connected with each other at their outer ends by springs, the bars having transverse apertures adapted to be engaged by 10 the outer ends of the said flexible support.

15 7. A moth-proof bag comprising a bag-body having a portion of one of its sides reinforced, the reinforced portion being apertured, a garment-support comprising an apertured back plate within the bag-body and a flexible support extending through the apertures of the said reinforced portion and the said back plate, and apertured washers interposed between the plate and the reinforced 20 25

portion of the bag-body and through which 30 extends the said flexible support.

8. A moth-proof bag comprising a bag-body, a pair of clamping-bars engaging the mouth of the bag-body for closing the same, a garment-support within the said bag-body 35 and extending through one side thereof to engage one of the said clamping-bars, and supplementary closing devices engaging the clamping-bars and the mouth of the bag-body.

40 9. A moth-proof bag comprising a bag-body, a pair of clamping-bars engaging the mouth of the bag-body for closing the same, a garment-support within the said bag-body and extending through one side thereof to 45 engage one of the said clamping-bars, and supplementary closing devices engaging the clamping-bars and the mouth of the bag-body, each supplementary closing device consisting of an elastic band and stiff end pieces. 50

In testimony whereof I have signed my name to this specification in the presence of two subscribing witnesses.
